UNITED STATES PATENT OFFICE

2,051,639

WIRING GRILLE AND METHOD OF
MAKING THE SAMEEdward H. Kalmbacher, Collingdale, Pa., assignor
to General Electric Company, a corporation of
New York

Application September 19, 1935, Serial No. 41,251

7 Claims. (Cl. 29—155.5)

For certain kinds of electrical work, it is important to have a means capable of supporting a large number of insulated current carrying wires, which may be readily attached to and removed from some fixed structure or support. An example of a means for such purposes is found in the patent to Reed and Paxton, No. 2,006,150 issued June 25, 1935, therein referred to as a perforated wiring strip and through which insulated wires extend. For reasons of economy of manufacture and reduction in size, it is desirable to make the wiring strip or grille out of thin metal, such as sheet steel. To provide a grille suitable for a large number of wires means that it must have a correspondingly large number of openings or perforations to receive the circuit wires. Because the number and arrangement of the wires on one panelboard or equivalent device may differ from those of another and because for manufacturing reasons the grilles should be made in quantities from the same set of dies, they are provided with a much larger number of holes or perforations than are commonly necessary for any particular piece of work. To save space in or on the structure using the grille and also to save stock in the grille itself, the openings or perforations, which are small in diameter, are made as close together as possible, leaving only such an amount or section of metal between holes as will afford a suitable support. To simplify the wiring as a whole, each wire depends upon its own insulation as protection from ground and short circuits. It is a simple matter, of course, to punch with an ordinary punch and die a lot of spaced holes in a strip of metal but in so doing a small burr will be left in many, if not all, cases on the side of the strip through which the punch protrudes on its working stroke. These burrs are liable to injure the insulation on the wires, particularly if the same portion of a wire is pulled through two burred openings in succession, and hence are a potential source of danger. Even if the burrs are removed, there still remains the danger of injuring the insulation due to the relatively sharp edge of the thin wall of the opening.

An object of my invention is the provision of an improved metal grille for wire supporting purposes wherein the walls of the perforations are so rounded or curved on both sides of the grille that insulation on the wires supported thereby is amply protected against cutting or other injury as the wires are pulled into place.

55 A further object of my invention is an improved

method of making wiring grilles of thin metal and specifically in the method of forming the walls of the perforations therein so that the ends thereof will present smooth curved unbroken surfaces on both sides of the grille.

For a consideration of what I believe to be novel and my invention, attention is directed to the accompanying description and the claims appended thereto.

In the accompanying drawing, which is illustrative of my invention, Fig. 1 is a plan view of my improved wiring strip; Fig. 2 shows on a greatly enlarged scale the die means for performing the first operation in the formation of the holes or perforations in the wiring strip; Fig. 3 is the die means for the second operation, and Fig. 4 the die means for the final or curling operation.

Numerals 5 indicates the wiring strip or grille which is made of thin sheet steel. As an example, it may be made of No. 16 gauge steel having a thickness of approximately .065 of an inch.

It is provided with a large number of perforations or openings 6, arranged in rows and with only enough metal between them to properly define the walls. It has been found by arranging or spacing the openings in parallel rows as shown that the largest number for a given surface area may be made. Should the requirements for the grille be less exacting, a greater pitch distance or spacing between openings may be employed. In other words, a greater amount of stock between openings may be provided.

It will be seen that the amount of metal between the walls of any two adjacent openings is very small and therein lies one of the chief difficulties of manufacture. Because of the thinness of the stock of which the grille is composed and because the amount of metal between two adjacent openings is so small, it is impractical to punch the openings and at the same time draw the metal of the sheet stock to any substantial extent around each opening from which to form a well rounded exit. The metal disk which results from cutting the metal to form each opening and which ordinarily would be waste material in its entirety is in my construction partially utilized. The small saving in metal is, of course, not material, the important fact is that without utilizing the waste material as disclosed herein, the desired formation of the exit wall of the opening on the back of the grille would not be attained. Briefly stated, I utilize a portion of the metal of the disk from each opening to form a flange on the back side of the grille which is subsequently curled outwardly from the axis of the opening to form a

smooth curved surface over which a wire may be pulled without injury to its insulation.

A portion of the disk sufficient to form a suitable small flange on the back side of the grille is obtained by the use of suitable dies such as is shown in Fig. 2, wherein 5 indicates the stock of which the grille is composed on a greatly enlarged scale. Numeral 8 indicates the body of the die, the wall of which is slightly tapered outwardly at its upper end as indicated at 9 to afford a small 10 additional space for metal when subjected to heavy pressure. The upper corner of the die is also slightly rounded to prevent injury to the stock as the punch descends. Inside of the die and forming a part thereof is an insert 10 having 15 a crowned top surface 11. Numeral 12 indicates a drawing punch having a projection 13 on its under side of a depth somewhat greater than the thickness of the stock of the grille. Between the upper end of the projection and the body of the 20 punch is a fillet 14 of such radius as to form a smooth curved surface on the grille at the entrance of the wire receiving opening. It will be noted that the punch does not pass entirely through the stock. Because of that fact and be- 25 cause of the crowned upper face 11 of the insert where the pressure is highest, metal is caused by the heavy pressure exerted thereon to flow radially from the center toward slightly tapering wall 9 of the die and in so doing fill the entire space 30 between the punch and die except for the small annular space indicated at 15. The effect of this operation is to form a shallow inset 16 in the grille as viewed from the top surface thereof in Fig. 2, said inset having an annular wall of substantial 35 thickness but one which is less than that of the stock itself. The depth of the inset is greater than the thickness of the sheet stock, the purpose being to provide material for a flange on the back 40 side of the stock as will appear later. Having properly formed the inset, the next step is to punch out the small disk situated within the annular wall. This is done by a piercing punch 17 and a piercing die 18 as shown in Fig. 3. The 45 result of this operation is to remove the small center part or disk and leave an annular flange 19 of substantial radial thickness, and one having a uniform and sufficient depth. By forming the flange in the manner described, it will be noted 50 that the section of metal between openings or perforations has not been disturbed.

After the flange is formed, the stock is ready for the third operation which consists in curling the flange so that it will present a smooth curved 55 surface to the entering circuit wire. This is done by a curling punch 20 having an upwardly extending projection 21 and a well rounded seat at the bottom thereof. In this case, pressure is applied to the stock of the grille by the flat punch 60 22 which causes the metal of the flange to curl as the pressure is applied.

As the net result of the operations above described, the wall of the opening or perforation in the grille is well rounded on both sides of the 65 grille and no sharp edges or projections remain to cut or injure the insulation on the circuit wires as they are threaded back and forth through the grille.

For simplicity, the several operations have been 70 described with respect to a single opening or perforation. In practice, however, a plurality of perforations should be treated simultaneously and in like manner. For example, it has been found satisfactory to operate simultaneously on as many 75 as twenty-eight, although a greater or lesser

number may be so treated. The wiring grille may be made in long or short lengths as desired, the strip of metal being fed longitudinally between the dies for the successive operations.

In order that the grille may be properly supported on the panelboard or other structure, a 5 series of slots or openings 23 is formed along the bottom edge to receive clamping screws carried by brackets or other devices on the panelboard or other structure. These slots may be pierced simultaneously with the perforations or separately, 10 whichever is the more convenient.

In many cases, it is desirable to support various wiring devices on the grille instead of securing them to the back of the panelboard. For this purpose, one edge, say the upper edge, of the grille 15 has a row of holes 24 which are adapted to receive clamping screws. The holes are closely spaced and their pitch distance bears no exact relation to the parts to be supported thereon. The main consideration is to have holes so closely spaced 20 and extending for a sufficient portion of the length of the grille as to permit securing in place of various wiring devices.

What I claim as new and desire to secure by Letters Patent of the United States is:

1. As an article of manufacture, a wire support comprising relatively thin elongated sheet metal stock having a series of openings therein each of which has an inwardly curved entrance wall and an outwardly curled flange integral 30 with the stock on the back side thereof and of larger diameter than the opening, said flange projecting from the back wall of the stock and defining an outwardly curved exit for the opening.

2. As an article of manufacture, a wire supporting grille comprising a strip of thin metal having numerous openings to receive insulated wires, the wall at the entrance of each opening 40 being curved on a small radius and the wall at the exit of each opening being formed by a thickened and outwardly curved portion of the stock of the strip.

3. As an article of manufacture, a wire supporting grille comprising a strip of thin sheet metal having a large number of openings arranged in rows with narrow walls between them, the entrance wall of each opening being curved 50 and the exit wall thereof formed as an integral outwardly curled portion of the metal of which the strip is composed.

4. As an article of manufacture, a wire supporting grille comprising a thin flat strip of metal having a large number of closely spaced wire receiving openings, each of said openings having a curved entrance wall and a thickened outwardly curved exit wall, openings along one edge of the grille to receive supporting means therefor, and a row of closely spaced openings on the opposite edge forming means to receive supports for devices to be carried by the grille.

5. The method of making a wire support from sheet metal which comprises forming an inset therein with a curved entrance wall, the depth of the inset being greater than the thickness of the sheet stock, removing the disk of metal defined by the inner wall of the inset to form an annular flange, and curling the flange outwardly 70 from the axis of the opening to form a smooth rounded exit surface therefor.

6. The method of making wire supporting grille having a large number of closely spaced wire receiving openings which comprises first 75

forming an inset with a curved entrance for each opening, removing the disk of metal defined by the inner wall of the inset to form an annular flange, and curling the flange away from the axis 5 of the opening to form a smooth rounded surface therefor.

7. The method of making wire supporting grilles having a large number of spaced wire receiving openings with narrow walls between them

which comprises forming an inset with a curved entrance for each opening, causing metal to flow radially outward from the center of the inset partly to form the side wall thereof, removing the disk of metal defined by the side wall of the inset to form a flange, and curling the flange away from the axis of the opening to form a smooth rounded surface therefor. 5

EDWARD H. KALMBACKER.
